BY ATTORNEY

Patented Nov. 20, 1923.

1,475,113

UNITED STATES PATENT OFFICE.

JULIUS B. GROND, OF NEW YORK, N. Y.

EVAPORATIVE REFRIGERATOR.

Application filed October 4, 1920. Serial No. 414,428.

To all whom it may concern:

Be it known that I, JULIUS B. GROND, a citizen of the United States, residing at New York city, in the county of New York and State of New York, have invented new and useful Improvements in Evaporative Refrigerators, of which the following is a specification.

This invention relates to improvements in iceless coolers, and one of the principal objects is to provide a device of this character whereby air may be cooled by forcing it through a moistened fabric.

Another object is to provide improved fabric moistening means.

Another object is to provide a device of this nature which may be used in a refrigerator or provision cooler and which may be removed therefrom and secured to the wall of a room for cooling the air thereof or for distributing disinfecting deodorizing or perfuming solutions.

With these and other objects in view, the invention consists of certain novel construction and combination and arrangement of parts, the essential features of which are hereinafter described and claimed, and which are fully illustrated in the accompanying drawings comprising two sheets, in which:

Figure 1 is a transverse vertical section of my device as applied to a refrigerator or provision cooler.

Figure 2 is an elevational view showing the device removed and hung on a wall.

Figure 3 is a detail view of the tank filling device taken substantially on line 3—3 of Figure 1.

Figure 4 is a detail of the float and connected telltale.

Like characters of reference refer to like parts in all views.

This invention contemplates the providing of a provision container with a device comprising a water tank which automatically feeds water into a trough from which it is distributed by capillary attraction to a screen stretched on a frame in front of an electric forcing fan, the frame being provided at its lower margin with a gutter for catching and carrying off superfluous moisture.

Referring more particularly to the drawing, 1 represents the walls of a refrigerator food container which may be divided by partitions 2 into a plurality of chambers

3, 4 and 5. Any desired number of chambers may be provided but only three are shown in the drawings. The partitions 2 are provided with apertures 6 which provide means for permitting a free circulation of air through the chambers and with air outlets or vents 7. A partition 8, preferably of metal is provided at the side of chambers 4 and 5 so as to divide off a space or chamber 9, and is provided with a large number of perforations 10 which permit the entrance of air from chamber 9 into chamber 5. Suitable doors (not shown) are provided at the front of the structure for closing the chambers 3, 4, 5 and 9.

A slide 11 is mounted on the side wall 1 of chamber 9 and mounted on this slide is a liquid container or tank 12. This tank is provided with an aperture 13 in its top over which is secured a rubber gasket 14. A filling member 15 is provided with an end 16, and a rivet or bolt 17 unites the members 14 and 16 to the top of the tank. The end 16 has an aperture 18 adapted to be moved into and out of register with the aperture 13 and the corresponding opening in the gasket. Filling member 15 may be provided at its free end with an enlargement or funnel 19. It will be readily seen that by turning the member 14 so that its aperture 18 registers with the aperture 13, the tank may be filled while by turning the member 14 so that its aperture 18 is over a solid portion of the gasket 14, the tank is sealed as far as aperture 13 is concerned. A small aperture 20 is provided at the bottom of the tank, said aperture opening into a trough 21. It will be readily understood that water will be emitted from aperture 20 until trough 21 is sufficiently filled to bring the water in the trough high enough to seal opening 20, and that the water will be automatically maintained at such level. A stopper is provided for closing aperture 20 during filling of the tank.

A curved flange 22 is provided at the edge of trough 21 and secured to this flange in any suitable manner is a depending frame 23 on which is tightly stretched a fabric curtain 24 provided at the top with a flap or wick 25 which is thrown up over flange 22 and hangs in trough 21 from which it draws the water by capillary attraction and conducts such water to the curtain 24. A gutter 26 is located below the bottom of frame 23 and is adapted to catch the super-

fluous water from the curtain 24 and to empty the same into an overflow pipe 27 leading to a drip pan 28 or other suitable receptacle.

5 A fan of the type known as a scoop or forcing fan is conventionally shown at 29 and may be operated from any suitable battery or other source of power. This fan may be of the stationary shaft type or of 10 the oscillating type, but in the latter case the tank, and its trough and curtain would be made of a correspondingly curvilinear form. Air may be conducted into chamber 9 by pipe 30 or any similar device. If 15 preferred, the fan may be dispensed with and air may be forced through the curtain from nozzles connected with an air compressor or like device.

The board or slide 11 is also provided 20 with a plurality of apertures 31 so that if it is desired to cool or disinfect the air of a room, the slide 11 may be removed from wall 1 by sliding it endwise in the grooves and may be secured to the wall of the room 25 or other suitable support with the curtain dropping over any wall fan, as shown in Figure 2.

It will of course be understood that the 30 air from the fan in being forced through curtain 24 is cooled by the evaporation of the liquid, and that this cooled air passes in turn into chambers 5, 4 and 3 and is then expelled through vents 7.

The lever 31 is pivoted to inside of the 35 front end of the tank, and is provided at one end with a float 32 and at the other with an indicator plate for displaying through a window 33 suitable indices showing the height of the water in the tank.

40 When the device is to be removed from

the main casing and hung on the wall, a screen 35 is secured to it as shown in Figure 2, so as to take the place of the perforated wall 8.

While I have described what I deem to be the most desirable embodiments of my invention, it is obvious that many of the details may be varied without in any way departing from the spirit of my invention, and I therefore do not limit myself to the exact details of construction herein set forth nor to anything less than the whole of my invention limited only by the appended claim.

What is claimed as new is:—

In a refrigerator of the evaporative type, the combination with a casing having a perforated partition forming a separate chamber in which is supported a cooling unit, including an air circulating fan, of a reservoir arranged in the chamber and having its bottom extending horizontally beyond one side wall thereof, a semi-circular flange extending upwardly and thence downwardly from the outer edge of the extended bottom, 60 said extended bottom and flange respectively defining a trough feed from the reservoir through the medium of the relatively small openings formed therein adjacent the bottom thereof and said opening being arranged so as to maintain the same level of water in the trough until the reservoir is emptied, a wick having its upper end secured to and following the curvature of the flange and being vertically arranged between the fan and the perforated partition for the purpose specified.

In testimony whereof I have affixed my signature.

JULIUS B. GROND.
